FIG. 1 is a top-front perspective view of the design for an electrical charger and docking station;
 FIG. 2 is a bottom-rear perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof; and,

FIG. 8 is a right-side view thereof.

The broken lines shown in the drawings are included for the purpose of illustrating environmental structure and form no part of the claimed design.
